W. H. JONES

SHADE HOLDER FOR LIGHT UNITS

Filed August 11, 1924

Inventor:
William H. Jones,
by *Alexander S. Jones*
His Attorney.

UNITED STATES PATENT OFFICE.

WILLIAM H. JONES, OF SCHENECTADY, NEW YORK, ASSIGNOR TO GENERAL ELECTRIC COMPANY, A CORPORATION OF NEW YORK.

SHADE HOLDER FOR LIGHT UNITS.

Application filed August 11, 1924. Serial No. 731,253.

To all whom it may concern:

Be it known that I, WILLIAM H. JONES, a citizen of the United States, residing at Schenectady, in the county of Schenectady, State of New York, have invented certain new and useful Improvements in Shade Holders for Light Units, of which the following is a specification.

My invention relates to globe or shade 10 holders and has for its object the provision of a simple, effective and comparatively inexpensive device for holding a shade in place.

The device is hereinafter fully set forth 15 and claimed, reference being had to the accompanying drawing in which Fig. 1 shows a form of the device for holding a single piece shade or globe; Fig. 2 shows a form 20 of the device for holding a two-piece globe, both of which pieces are of approximately the same thickness; Fig. 3 shows a form of the device for holding a two-piece globe, one of the elements of which is thicker than the other.

Referring more in detail to the drawing, 25 the holder in the preferred form shown consists of an angular portion 2 having shoulder 3 and an inner flange 4. About its periphery the holder is provided with suitably threaded holes 5 through which screws 30 project for clamping the holder to any suitable support. As indicated in Fig. 1, the globe 6 may be provided with a flange 7 adapted to rest in the shoulder 3. On the 35 underside of the holder there is provided a ring 8 which is secured to the holder by means of suitable screws 9 which are threaded into the flange 4. Between the ring 8 and the shoulder 3 the flange 7 of the globe is 40 wedged tightly in place. It will be understood that if desired any suitable form of bushing may be inserted between the globe and the holder.

It will be understood that the neck portions 10 of the holder may be made of different lengths so as to accommodate globes of 45 different styles. The holder in Fig. 1 is

shown with a rather short neck, while the holder in Fig. 3 is shown with a somewhat longer neck, and the holder in Fig. 2 is 50 shown with a still longer neck in order to accommodate the two sections of the globe which are shown as being thicker than the section in Fig. 3.

With a holder of this type, it is readily 55 seen that the globe may be removed by merely removing the ring 8. On the other hand, the globe may be readily clamped into position by merely slipping the globe into position against the shoulder of the holder 60 and securing the ring 8 in place by the screws.

What I claim as new and desire to secure by Letters Patent of the United States, is,—

1. A shade holder for a light unit having 65 an element formed with two annular rings, an outer one and an inner one, and a shoulder located between the two rings, a second shoulder projecting toward the axis of the holder from one end of the inner annular ring in combination with a washer, and means for securing said washer to said element in the region of the second shoulder, 70 said washer projecting beyond the inner ring, together with a shade consisting of 75 two elements each having a radial flange and constructed so that one flange may be seated upon the other and the two flanges seated against the first shoulder of said element, and both flanges clamped in position 80 by said washer.

2. A shade for a light unit consisting of 85 two separate glass elements each having a radial flange on one end and constructed so that one flange may rest upon the other, both elements being flaring in form, said elements constructed so that their rims on the opposite side of the flanges come together thereby forming a closure with a hollow space 90 between the two elements, and means for clamping the two flanges together.

In witness whereof, I have hereunto set my hand this 9th day of August, 1924.

WILLIAM H. JONES.
